Patented June 6, 1916.

UNITED STATES PATENT OFFICE.

EDWARD M. DEEMS, OF NEW YORK, N. Y.

PRIMARY BATTERY.

1,186,084.

Specification of Letters Patent. Patented June 6, 1916.

Application filed June 28, 1915. Serial No. 36,427.

To all whom it may concern:

Be it known that I, EDWARD M. DEEMS, a citizen of the United States, and resident of the borough of Manhattan, city, county, 5 and State of New York, have invented certain new and useful Improvements in Primary Batteries, of which the following is a specification.

One of the main objects of this invention 10 is to so construct the parts of a primary battery that said parts may be cheaply manufactured and very conveniently assembled.

Another object of the invention is to so construct the parts of a primary battery 15 that the recharging of the battery may be very conveniently accomplished.

There are other important objects and advantages of the invention, relating more particularly to the construction and arrangement of the battery elements and the support therefor, all of which will be more fully hereinafter described.

In the drawing, Figure 1 is a vertical sectional view of the battery complete; and 25 Fig. 2 a plan view of the battery element supporting ring.

Referring to the various parts by numerals, 1 designates the ordinary battery jar and 2 the cover thereof. Secured to the center of the cover is a depending rod 3, said rod being detachably connected to the cover by means of the lock nut 4. This rod forms one terminal of the battery and secured on the upper end thereof is an ordinary binding nut 5. Connected to the lower end of rod 3 and supported within the battery jar by said rod is a central hollow metal shell 6. This shell is tapered at its upper end, and is provided at its lower end with a horizontal 40 outwardly extending annular flange 7. This shell is preferably cylindrical in transverse section and is open at its lower end but closed at its upper end. Resting on and supported by the flange 7 is a porcelain ring 8, said ring being formed with the outwardly extending radial arms 9 at suitable points around its circumference. Each of these arms is provided with an upwardly extending lug 10, the inner surface of said lugs being substantially in the same vertical plane as the outer surface of the supporting ring 8. The upper surfaces 11 of these lugs incline inwardly and downwardly, as shown in Fig. 1, the lower edge of this inclined surface being a short distance above the upper 50 surface of the ring. Each arm at its outer

end is formed with an upwardly extending lug 12, a space 13 being formed between the lugs 10 and 12.

Surrounding the central cylindrical shell 60 6 is a perforated sheet metal cylinder 14, said cylinder being substantially equal in diameter to the supporting ring 8 and held in place by the lugs 10. At the lower end of this perforated cylinder is formed an inwardly extending annular flange 15 which rests on the supporting ring 8 and the inner marginal edge of this ring is turned upwardly to form the upwardly and inwardly inclined flange 16 which fits closely against 70 the outer surface of the shell 6. It is preferred to have the flange 16 so disposed that its upper edge will fit closely against the hollow central shell 6 when the parts are assembled, said shell then forming a cylindrical central hollow post extending up into the perforated metal cylinder 14. The narrow annular space between the shell 6 and the perforated cylinder 14 is designed to receive the negative element, said element being any desired form of flaked or pulverized, oxidized copper. The cylinder 14 is substantially equal in height to the shell 6, and the walls of said cylinder and said shell are parallel up to the tapered top of the 85 shell 6. The negative element fills the space between the two metal parts and rests on the inwardly turned flange 15 of the cylinder. The central shell 6 forms one terminal of the battery circuit and the conductor rod 90 3 is connected thereto. The cylinder 14 rests loosely on the top of the supporting ring 8 and may be removed therefrom whenever it is desired to recharge the battery with the negative element. 95

The positive or zinc element 17 is preferably cylindrical and tubular in form, of larger diameter than the perforated cylinder 14 and adapted to rest on the arms 9 in the space 13 between the lugs 10 and 12. 100 The lower end of the zinc is preferably in the same horizontal plane as the bottom of the perforated cylinder 14 and its upper end is preferably in a horizontal plane with the upper ends of the parallel walls of the 105 central shell or post, so that the respective lengths of the positive and negative elements are substantially the same. This zinc rests loosely on the arms 9 and may be readily removed therefrom. The lugs 110 12 not only prevent the displacement of the zinc from the supporting arms, but also

serve as a means for preventing the zinc contacting with the sides of the battery jar. The lugs 10 between the zinc and the negative element, space the zinc away from the negative element and prevent the said two elements contacting at any time. The upper surfaces of the lugs are beveled downwardly and inwardly to prevent any copper particles lodging thereon. Any copper dust settling on said surfaces will be caused to fall therefrom so that there will be no danger of a bridge of copper or copper dust being formed from the negative copper element to the zinc element.

15 It is manifest that I produce a primary battery the parts of which are of extremely simple construction and may be very cheaply and readily manufactured; and which will permit of a ready and economical recharge. All of the parts are readily detachable so that lost or broken parts may be readily replaced when the battery is recharged. The metal shell 6 is in direct contact with the entire body of the negative element, and, therefore, forms an excellent terminal.

In assembling the parts of the battery it is manifest that first the porcelain ring is placed around the central support 6 and brought to rest on the flange 7. The perforated cylinder 14 is then placed around the support with its bottom flange 15 resting on the porcelain ring. The upwardly extending flange 16 bears closely against the shell 6 and forms a comparatively close joint therewith. The flaked copper is then placed in the narrow annular space between the shell 6 and the perforated cylinder. The zinc element is then placed in position, 40 and said zinc element is preferably of the same height as the column of flaked copper. The effective lengths of the copper and the zinc are directly opposite each other so that their entire effective lengths are 45 utilized. When the parts are assembled as described the suspending rod 3 is secured to the battery jar cover and then the assembled parts are ready to be placed in the jar.

It is manifest that the porcelain insulating ring may be used in conjunction with various forms of central supports and with various constructions of negative elements. This ring forms a readily removable supporting means for the zinc element and may, 55 be readily slipped over any form of negative element, it being only necessary to provide means similar to the flange 7 for supporting it at or near the lower end of said element. The said ring and its radiating arms will then form an insulating support for a zinc element, with all the advantages hereinbefore set forth.

It will also be noted that the porcelain ring together with its radial arms and up- 60 standing lugs 12 form a unitary structure

which affords an efficient support for the battery elements, whereby all the parts may be readily assembled in the jar and supported in their most effective relative positions without the use of bolts or other fastening devices and whereby also the supporting device as an entirety may be removed from its central hanger (in this instance, a depending shell 6) when it is desired to clean or renew the battery elements. In removing the cylinder 14 it is withdrawn upwardly off the internal shell 6 so that the annular lip 16 shall perform the office of a scraper, thereby removing from the external surface of the shell 6 any deposits that may have 75 formed thereon.

It will be also seen that a feature of importance lies in so disposing the upstanding lugs 12 at the outer extremities of the radial arms that they engage the zinc cylinder on its outer face so as to thereby avoid interfering in any way with the proper action of the battery elements.

It will be observed also that whether the ring 8 be supported directly on a part of the central hanger member 6 or indirectly thereon, in all cases the ring will be guided and centered by its support and also be readily removable as an entirety by being slipped off one end or the other of the central hanger member.

What I claim is:

1. A battery comprising a central metal cylindrical support formed with an outwardly extending flange at its lower end, 100 a ring of insulating material loosely supported on said flange and surrounding said central support, outwardly extending arms formed on said ring, an upwardly extending lug being formed on each of said arms, 105 a perforated metal cylinder supported by the ring between said lugs and the central support, said cylinder forming a narrow annular channel of uniform dimensions throughout and adapted to contain the negative element, an upwardly extending lug at the outer end of each of said arms, said lugs serving to hold the positive or zinc element in place and to prevent said element contacting with the battery jar.

2. A primary battery consisting of a jar and a cover therefor, a central suspending member forming one terminal of the battery, a unitary support for the battery elements consisting of a ring removably supported on the lower end of said central member and provided with a plurality of radial arms, each of which is provided with an upstanding lug, and battery elements supported on said support, the positive element 120 being centered and supported by said upstanding lugs.

3. A primary battery consisting of a jar, a cover therefor, a hanger member depending from the cover and forming one termi- 125

- nal of the battery, an insulating support removably supported at the lower end of said hanger member and consisting of a ring surrounding the hanger member and provided with a plurality of radial arms, each having an upstanding lug, a cylindrical zinc element resting on said arms and centered by said lugs, and means surrounding the aforesaid hanger member and forming therewith the negative pole.
4. A primary battery consisting of a jar, a central supporting member forming the negative terminal of the battery, and means for removably supporting thereon the remaining elements of the battery, said means embodying a unitary structure consisting of an insulating ring surrounding and removably supported on said support and adapted to be removed by being slipped off one end thereof, said ring being provided with a plurality of radial arms, each of which is provided with an upstanding lug for supporting and centering the positive element of the battery.
5. A primary battery consisting of a jar, a central supporting member forming the negative terminal of the battery, and means for removably supporting thereon the remaining elements of the battery, said means embodying a unitary structure consisting of an insulating ring surrounding and removably supported on said support and adapted to be moved by being slipped off one end thereof, said ring being provided with a plurality of radial arms, each of which is provided with an upstanding lug for supporting and centering the positive element of the battery, said lugs being at the extreme outer ends of the radial arms so as to engage the outer face of the positive element, for the purpose set forth.
6. In a primary battery, the combination of a jar, a cover therefor, a depending cylindrical member forming one terminal of the battery, means for removably supporting the elements of the battery upon the lower end thereof, the negative element of the battery embodying a perforated cylinder having at its lower end an inwardly-extending flange forming the bottom of the chamber of the negative element and impinging against the exterior surface of the aforesaid depending member, whereby when said perforated cylinder is slipped off the end of the said cylindrical member said flange will serve to scrape the exterior surface of said member.
7. In a primary battery, the combination of a jar, a cover therefor, a central supporting member forming one terminal of the battery, an insulating ring support removably supported thereon and provided with a plurality of radial arms, each of which is provided on its upper surface with two spaced upstanding lugs, the inner lug having its upper surface beveled downwardly, and removable battery elements supported on said ring and its arms, the beveled lugs extending up between the negative and positive battery elements so that their inclined surfaces will serve to shed or deflect deposited substances toward one of the battery elements and thus prevent internal short-circuiting of the battery.

In testimony whereof I hereunto affix my signature.

EDWARD M. DEEMS.
